UNITED STATES PATENT OFFICE.

THEODORE PETERSON, OF AKRON, OHIO, ASSIGNOR TO THE HOWARD MANUFACTURING COMPANY, OF SAME PLACE.

GYMNASTIC LIVE BALL.

SPECIFICATION forming part of Letters Patent No. 450,185, dated April 14, 1891.

Application filed October 22, 1890. Serial No. 368,892. (No model.)

To all whom it may concern:

Be it known that I, THEODORE PETERSON, a citizen of the United States, residing at Akron, in the county of Summit and State of Ohio, have invented a certain new and useful Improvement in Live Balls for Gymnastic Exercise, of which the following is a specification.

My invention has relation to improvements in the manufacture and construction of that class of gymnastic exercising apparatus known as the "live ball," and which consists of an inflated spherical bag, usually constructed of an inner air-tight rubber bag protected by an outer case of soft leather or analogous substance to which the suspending-cord is attached. As ordinarily constructed, the cases have a straight cut or slit for the introduction and removal of the rubber bag, which slit is closed by laces, and the cords have usually been attached to the outer case by means of a strap retained by rivets and washers. This construction is objectionable because of the time required in closing the opening in preparing the ball; and also because the projecting rivets and washers present rough edges, which can and frequently do injure the hands of persons in the active use of the ball.

32 The object of my invention is to overcome these objections; and it consists in the peculiar and novel construction and arrangement of parts hereinafter described, and then specifically pointed out in the claims, reference being had to the accompanying drawings, which form a part of this specification.

In the accompanying drawings, in which similar letters of reference indicate like parts, Figure 1 is a vertical central section of the upper part of my improved live ball, showing the method of closing the opening in the case and the manner of attaching the suspending-cord and protecting the union; Fig. 2, a perspective of the several parts of the case-opening, showing their construction and arrangement; Fig. 3, a plan of the same with the cord and guard removed; Fig. 4, a perspective of the upper part of the ball closed with cord and guard attached; Fig. 5, a perspective of the cord, hook, and guard, the bell of the latter

turned back to permit the ready attachment to the ball; and Fig. 6 a perspective, looking from below, of the lower part of the guard and supporting-hook.

The outer case A is of soft pliable leather or analogous material arranged to receive and inclose the rubber bag B, which is of the ordinary construction, and is provided with a flexible tube b, by which it is inflated after being inserted in the case, and by twisting which the air is retained. At the union of the pieces of which the case A is formed is preferably attached a re-enforcing disk-piece D, in the center of which is a circular opening and from which extend radial cuts C, thus presenting inwardly-folding points. In one of these points thus formed is attached a metallic plate bearing a stud E, having an opening to receive the hook of the suspending-cord, and attached to the other points are perforated plates F F' F'', arranged to receive the stud E, and so disposed with relation to each other that, the point bearing the stud E having been turned down, the plates F F' F'' are successively placed on said stud and both close the bag-opening and cause it to present an even spherical contour.

The suspending-cord G is provided with a hook H, arranged to enter the opening in the stud E, and thereby suspend the ball and retain the plates F F' F'' in place. About the cord G and inclosing its union with the hook H is a guard I of the form shown, of any desired material, but preferably of soft vulcanized rubber, and so situated that its lower edges will, when the hook is inserted in the stud-opening, rest on the top of the case and inclose the openings.

I do not limit my invention to the exact number of points shown, as these may be reduced or increased; but

What I claim, and desire to secure by Letters Patent, is—

1. The combination, with an elastic ball arranged to be inflated and provided with means for preventing the escape of air therefrom, of a flexible cover provided with an opening consisting of cuts radiating from a common center, forming points, to one of which is attached a stud provided with an opening to re-

ceive a hook, and from the other points perforated plates arranged to fit on said stud, substantially as shown and described.

2. The combination, with a case for a ball 5 of the class designated and provided with a projecting stud having an opening to receive a supporting-hook and a hook and cord arranged to support said ball, of a funnel-shaped guard, of flexible material, arranged to inclose

said hook and have the edges of its larger end 10 rest on said ball, substantially as shown and described.

In testimony that I claim the above I hereunto set my hand.

THEODORE PETERSON.

In presence of—

C. E. HUMPHREY,
C. P. HUMPHREY.
